UNITED STATES PATENT OFFICE.

HUGO SUNDSTEDT, OF NEW YORK, N. Y.

AIR-PROPELLED BARGE.

Application filed April 28, 1926. Serial No. 105,297.

This invention relates to air propelled barges such as are commonly used on inland shallow waterways and has for an object to propel barges of this kind by an air propeller instead of a water propeller, and a further object is to mount the propeller on a swivel stand whereby its direction relative to the barge can be changed or varied with the object of moving the barge sideways as well as forwards or backwards. Other objects of the invention will appear from the following specification and the accompanying drawings in which, Fig. 1 is a plan view of a barge embodying my invention, Fig. 2 is a side elevation of the barge shown in Fig. 1, Fig. 3 is a longitudinal section of the rear end of the barge showing the operating mechanism for the air propeller, Fig. 4 is a sectional elevation of the pedestal supporting the propeller and Fig. 5 shows another arrangement of pedestal supporting the motor and propeller.

Canal barges of the type shown usually have a shallow draft and are moved along by a water propeller at a low speed. This propeller in shallow water stirs up the mud which gradually leads to an erosion of the banks and a settlement which reduces the depth of the canal bed and requires dredging at intervals to restore the normal depth of the water. By using an air propeller on the barge, this condition is substantially avoided. By eliminating the water propeller there is no fouling with objects in the channel and the barge can move in shallow water without danger of loosing its propeller.

Barges of the present type are usually docked by the aid of a tug boat which can move them in any direction. The air propeller in the present invention is mounted on a swivel and its direction of thrust relative to the barge is controlled from the pilot house so that it may be set to move the barge forward, or turned through 180° to move the barge backwards, or it may be set in any position to move the barge sideways in either direction, or to obtain a resultant of a forward and sideways motion. Thus, by proper manipulation of the propeller the barge can be placed as desired within the narrow limits of the docking space. This invention has a particular application to barges of shallow draft and comparatively high speed but may be ap-

plied to barges in general and is not restricted in any sense to this class.

Referring to the drawings, 11 is the hull, 12 is the deck, 13 is the pilot house, 14 is the bow which is constructed in transverse corrugations as indicated at 15. The rudder 16 is provided for steering the barge when it is being towed. The air propeller 17 is carried by the rotating head 18 mounted on the pedestal 19 through which a suitable driving mechanism, hereinafter described, operates the propeller and turns the head 18 in the desired direction.

In Fig. 3, the motor 21 is placed in the engine room 22 built into the hull and by shaft 23, bevel gears 24, shaft 25, bevel gears 34, Fig. 4, and shaft 35, drives the air propeller 17. The controlling wheel 26 in the pilot house 13, by bevel gears 27, shaft 28, bevel gears 29, shaft 30 and a bevel gear connection rotates shaft 31 carrying the spur gear 39 at its upper end which meshes with the internal gear 40, Fig. 4, in the head 36. This head is supported by the pedestal 19 through the sleeve 33 and rotates on the ball bearings 37 and is held in place by the clamping ring or collar 38 and by the shaft 25. The pedestal is secured to the deck by the bottom flange 32.

It will be noted from Figs. 3 and 4, that the head 36 is capable of rotating on its support about shaft 25 as a centre and may be rotated while the propeller is in motion. The head 36 is rotated in response to the controlling wheel 26 and thus the direction of the thrust from the propeller on the barge is controlled from the pilot house whereby the barge is effectively steered.

In the alternative form shown in Fig. 5 the motor and propeller are mounted to swivel about the pedestal so that a direct drive is obtained between the motor and the propeller shaft. The rotation of the motor and propeller is effected through a worm gear. The pedestal 51 is secured to the deck and is conical shaped. A sleeve 52 is placed over the pedestal as shown and rests upon the ball bearings 53-54. The lower flange of this sleeve is formed with worm teeth at 55 which are engaged by the worm 56 supported by the bracket 58. The worm 56 is rotated through the shaft 57 thereby carrying the sleeve 52 around the pedestal.

A bracket 60 formed integral with sleeve 110

52 supports the motor 21 and the head 59 carries the shaft 35 of the propeller 17. Means may be provided for remotely controlling the motor mounted on this turret which are not shown in the drawing in the present application.

It should be understood that more than one propeller can be provided on a barge and if desired a propeller can be provided 10 fore and aft and co-operatively controlled to drive and steer the barge.

The corrugations formed at 15 in the bow facilitate the movement of the barge in riding over the shallow waves formed by its 15 movement in the water.

Having thus described my invention, I claim:

1. In an air propelled barge, the combination, a barge with a hollow upstanding pedestal on the deck, a head rotatably mounted 20 on said pedestal and carrying a propeller, a driving shaft centered in said pedestal and operatively connected with said propeller and a second shaft in said pedestal operatively connected with said head for rotating said head and means below the deck for driving said driving shaft and means for operating said second shaft.

2. In an air propelled barge, the combination, a barge with a hollow pedestal on the deck, a head rotatably mounted on said pedestal and carrying a propeller, a collar securing said head to said pedestal, a driving shaft centered in said pedestal and operatively connected with said propeller and a second shaft in said pedestal operatively connected with said head for rotating said head.

3. In an air propelled barge, the combination, a barge with a hollow pedestal on the deck, a head rotatably mounted on said pedestal and carrying a propeller, an internal gear in said head, a driving shaft centered in said pedestal and operatively con-

nected with said propeller and a second shaft 45 in said pedestal geared to said internal gear for rotating said head.

4. In an air propelled barge, the combination, a barge with a hollow pedestal on the deck, a sleeve at the end of said pedestal, 50 a head rotating on ball bearings on said sleeve, a ring securing said head on said pedestal, a propeller shaft mounted in said head and a drive shaft operatively connected with said propeller shaft centered in said 55 pedestal.

5. In an air propelled barge, the combination, a barge with a hollow pedestal on the deck, a sleeve at the end of said pedestal, a head rotating on said sleeve and secured to 60 said pedestal, a propeller shaft mounted in said head, a drive shaft centered in said pedestal and operatively connected with said propeller shaft and a second shaft in said pedestal for rotating said head, said drive 65 shaft and said second shaft having bearings in said sleeve.

6. In an air propelled barge, the combination, a barge with a hollow pedestal on the deck, a sleeve at the end of said pedestal, 70 a head rotating on said sleeve, an exterior ring on said pedestal securing said head in place, a propeller shaft mounted in said head, and a drive shaft centered in said pedestal and operatively connected with said 75 propeller shaft.

7. In an air propelled barge, the combination, a barge with a hollow pedestal on the deck, a sleeve at the end of said pedestal, a head substantially the same diameter as 80 said pedestal mounted on said sleeve, a drive shaft centered in said pedestal and passing through said sleeve and the wall of said head, a horizontal shaft carrying a propeller mounted in said head and gears connecting 85 said drive shaft and said horizontal shaft.

In testimony whereof I affix my signature.
HUGO SUNDSTEDT.
